COMBINED STEAM CURLING IRON AND STAND THEREFOR

Paul O. Rawson, Easton, Conn., assignor to
Clairol Incorporated, New York, N.Y.

Continuation-in-part of design application Ser. No.
434,471, Jan. 18, 1974. This application May 14,
1975, Ser. No. 577,252

Term of patent 14 years

Int. Cl. D28—03
U.S. Cl. D86—10 E

FIG. 1 is a perspective view of a combined steam curling iron and stand therefor showing my new design;

FIG. 2 is a side elevational view thereof as viewed from the opposite side of the view of FIG. 1;

FIG. 3 is a top plan view thereof;

FIG. 4 is a bottom plan view thereof;

FIG. 5 is an end view thereof as viewed from the handle end.

This application is a continuation-in-part of my application, Ser. No. 434,471, filed Jan. 18, 1974, and titled Steam Curling Iron.

I claim:

The ornamental design for a combined steam curling iron and stand therefor, as shown and described.
